(57) **CLAIM**

The ornamental design for a vehicle or vehicle replica, as shown and described.

DESCRIPTION

FIG. 1 is a front-perspective view of a vehicle or vehicle replica, of the new design;

FIG. 2 is a rear-perspective view thereof;

FIG. 3 is a side view thereof;

FIG. 4 is a top view thereof;

FIG. 5 is a side view thereof, opposite that of FIG. 3;

FIG. 6 is a front view thereof;

FIG. 7 is a rear view thereof;

FIG. 8 is a bottom view thereof;

FIG. 9 is an enlarged and partial front view thereof, taken along line 9-9 of FIG. 6; and,

FIG. 10 is an enlarged and partial rear view thereof, taken along line 10-10 of FIG. 7.

The roof is generally transparent glass. The broken lines (e.g., "LUCID" text, door handles, mirrors, wheels, etc.) are for environmental illustrative purposes only and form no part of the claimed design.
